Motorola, Inc., Chicago, Ill., a corporation of Illinois

Application December 30, 1955, Serial No. 556,636

1 Claim. (Cl. 313—299)

The present invention relates to electron discharge devices and more particularly to a power tube that exhibits favorable characteristics of a pentode type and yet which incorporates more economical structure of the beam type.

The pentode power tube includes a well-known suppressor grid between the screen grid and plate electrodes of that tube. The suppressor is usually operated at cathode or ground potential, and it opposes the flow of secondary electrons from the plate to the screen which occurs in the usual tetrode. This opposition is due to the fact that an electrostatic field with a negative potential gradient is established in the vicinity of the plate, and this field returns the secondary electrons to the plate. This results in eliminating distortions in the plate-current vs. plate-voltage tube characteristics.

The beam power tube has been developed in an effort to duplicate the improved pentode characteristics with a tetrode type of structure. In the beam power tube, the electrons move from an elongated cathode to a surrounding anode in a series of sheet-like beams, and these beams function as an effective suppressor in the space between the screen grid and the anode due to the mutual repulsion between the electrons. That is, the beams themselves establish the needed negative potential gradient around the anode to return the secondary electrons thereto.

It is usual to construct beam power tubes with an essentially flat two-sided elongated cathode, with one set of beams emanating from one side of the cathode and traveling in one direction to the anode, and with another set of beams emanating from the other side of the cathode and traveling in the opposite direction to the anode. It has been found with beam power tubes of this type that it is difficult to duplicate the improved characteristics of the pentode, and discontinuities usually appear in the respective "knee" portions of its plate-current vs. plate voltage characteristic curves. These discontinuities are especially troublesome when the tube feeds into a resonant output circuit since there is a tendency to set up parasitic oscillations in the output circuit. These discontinuities are due to the focusing effects of the beam-forming electrodes in the tube on the oppositely directed electron beams in the two halves of the tube. In a manner to be explained, the beam forming electrodes set up electrostatic fields that have a tendency to produce focusing effects on the beams, and due to the difficulty in obtaining absolutely symmetrical structure on both sides of the tube, these focusing effects are different for the different beams and this produces the discontinuities in the above-mentioned characteristics and the resulting parasitic oscillations in the output circuit.

It is, accordingly, an object of the present invention to provide an improved electron discharge device of the beam power type which is not subject to the above-described disadvantages inherent in the prior art devices of this general type.

Another object of the invention is to provide such an improved beam power electron discharge device in which defects in the focusing effects of the beam-forming elec-

2

trodes within the tube are obviated for all practical purposes so as to improve the operating characteristics of the tube and to prevent undesired parasitic oscillations in the output circuit thereof.

5 A feature of the invention is the provision in an improved electron discharge device of the beam power type of one or more auxiliary wire electrodes established at the potential of the beam-forming electrodes and extending across the apertures or windows formed by these electrodes, so as to oppose adverse focusing effects within the tube, thereby to improve the translating characteristics of the discharge device.

The above and other features of the invention which are believed to be new are expressly set forth in the claims. The invention itself, however, together with further objects and advantages thereof, may be best understood by reference to the following description when taken in conjunction with the accompanying drawing in which:

20 Fig. 1 is a perspective schematic representation of a typical prior art beam power tube;

Fig. 2 shows schematically the electrostatic field set up in one half of the tube of Fig. 1;

25 Figs. 3 and 4 are representations of the tube of Fig. 1 modified in accordance with the invention;

Fig. 5 is a schematic representation of the electrostatic field set up in one half of the modified tube of the present invention; and

30 Fig. 6 is a cut-away view of the modified tube of the invention.

The invention provides an electron discharge device of the beam type which comprises a cathode adapted to emit electrons from opposite sides thereof, an anode structure having a first portion facing and spaced from one side of the cathode and a second portion facing and spaced from the other side of the cathode, a grid structure interposed between the cathode and the anode, and a beam-forming structure interposed between the grid structure and the anode for forming the electrons from the opposite sides of the cathode into a pair of oppositely-directed beams. The beam-forming structure has a pair of apertures or windows through which respective ones of the beams travel to the anode. The cathode and beam-forming structure are established at reference potential, and the grid and anode are established at different positive potentials during normal operation of the device. This causes electrostatic fields to be established in the windows of the beam-forming structure and these fields have a tendency to focus the respective beams in an asymmetrical manner and produce adverse operating characteristics in the tube. In accordance with the invention, at least one auxiliary electrode is positioned in each of the windows in the beam-forming structure and these auxiliary electrodes are established at the reference potential of the cathode and beam-forming electrodes to distort the electrostatic fields in such a manner that the beam focusing tendency of these fields is reduced to eliminate the above-mentioned distortions.

60 The electron discharge device of Fig. 1 includes an elongated essentially flat cathode 10 which is adapted to emit electrons from each of its opposite faces. The cathode is surrounded by a spirally-wound, wire, grid structure 11 which functions as the control grid; and structure 11 is in turn surrounded by a similar spirally-wound, wire, grid structure 12 which functions as the screen grid. The elements 10, 11 and 12 are, themselves, surrounded by an essentially rectangular-shaped anode 13, which has a first portion 13a facing one side of the cathode and a second portion 13b facing the other side of the cathode. A beam-forming structure in the form of a pair of beam-forming electrodes 14 and 15 are disposed on opposite sides of the screen grid,

and these electrodes define an aperture or window between each side of cathode 10 and the respective portions 13a, 13b of anode 13.

During normal operation of the tube, the cathode 10 and beam forming electrodes 14, 15 are established at a reference potential such as ground, and the screen electrode 12 and anode 13 are established at different positive potentials. For example, the screen electrode may be established at +150 volts direct current and the anode may be established at +60 volts direct current. The assembly is such that the electrons emitted by one side of the cathode 10 are formed into a first series of sheet-like beams directed at the anode portion 13a, and the electrons emitted from the other side are formed into a second series of sheet-like beams directed at the anode portion 13b. For convenience of description, each of these series will be referred to herein as but a single beam.

The electrostatic field set up in one of the windows of the beam-forming electrodes 14, 15 is shown in Fig. 2. As noted previously, the anode portion 13a is established at a positive direct-current voltage of, for example, 60 volts; the beam-forming electrodes 14, 15 are established at reference or ground voltage; and the screen electrode 12 is established at a positive direct-current voltage of, for example, 150 volts. These elements set up an electrostatic field in the aperture or window of the beam-forming electrodes 14, 15 as represented by the equi-potential lines a, b, c and d. The shape of these lines is such that the beam has a tendency to be defocused as it travels between the screen electrode and the window in the beam-forming electrodes and to be focused as it travels between the beam-forming electrodes and the anode portion 13a. A different defocusing and focusing effect is experienced by the oppositely-directed beam passing through the other window of the beam-forming electrodes 14, 15 to anode portion 13b. These different focusing effects of the electrostatic fields within the two halves of the tube produce discontinuities at the respective knee portions of the plate-current vs. plate-voltage characteristic curves of the tube, and this produces the undesired effects discussed previously herein.

In short, although the beam power tube attempts to achieve the desired operating characteristics of the pentode, the prior art tubes of this general type have fallen short of this goal and still exhibit characteristics similar to those of the usual tetrode.

In accordance with the present invention, one or more auxiliary electrodes 16, preferably in the form of thin wires, are positioned within each of the windows in the beam forming structure 14, 15. These auxiliary electrodes extend preferably along the longitudinal axis of these windows essentially parallel to the longitudinal axis of the cathode 10. As shown in Fig. 4, the auxiliary electrodes 16 are established at the potential of the beam-forming electrodes and the cathode. These auxiliary electrodes distort the electrostatic field in each of the windows in the beam-forming electrodes to oppose the focusing tendency of these fields. As shown in Fig.

5, for example, the auxiliary electrode 16 has a tendency to straighten out the equi-potential lines a, b, c and d of Fig. 2 to produce the lines e, f, g and h that have substantially less focusing effect on the beam so that the undesired results of such focusing are overcome for all practical purposes.

As previously noted, the windows in the beam forming electrodes are elongated and extend essentially parallel to the respective opposite faces of the cathode. The auxiliary electrodes 16 may conveniently be formed by welding wires to the beam forming electrodes so that they extend across each of the windows essentially parallel to the cathode.

Therefore, in accordance with the present invention, 15 one or more auxiliary suppressor electrodes in the form of the wires 16 are inserted in each of the windows of the beam-forming electrodes effectively to convert the beam power tetrode into a pentode insofar as its operation is concerned, so that the improved operating characteristics of the pentode may be obtained while still retaining the mechanical economies of the beam power tetrode.

I claim:

An electron discharge device of the beam type subject to exhibit an irregularity in the anode current-anode voltage characteristic curve when the anode potential is at a low positive potential with respect to the cathode and below the screen grid potential, including in combination an envelope for said device, an elongated cathode having a pair of opposite faces adapted to emit electrons therefrom, an anode electrode surrounding said cathode and spaced therefrom, control and screen grid electrodes surrounding said cathode and interposed in the order named between said cathode and said anode, 30 a beam forming structure interposed between said screen grid electrode and said anode, said beam forming structure having a pair of elongated windows one of which is associated with each of the faces of said cathode, means coupling said beam forming structure directly to said cathode for establishing the same at a common potential, and a conductor wire centrally positioned in each of said elongated windows and substantially in the plane thereof, such conductor wires extending longitudinally of said windows and being substantially parallel 35 to said elongated cathode, said conductor wires being supported by said beam forming structure and directly electrically connected thereto internally of said envelope for establishing the same at a common potential, thereby modifying the electrostatic field through which the 40 electrons travel from said screen grid electrode to said anode electrode.
